UNITED STATES PATENT OFFICE.

ALBERT WANNER, JR., OF HOBOKEN, NEW JERSEY.

OPERA-CHAIR.

931,821.

Specification of Letters Patent. Patented Aug. 24, 1909.

Application filed February 11, 1908. Serial No. 415,330.

To all whom it may concern:

Be it known that I, ALBERT WANNER, Jr., a citizen of the United States, residing in Hoboken, Hudson county, New Jersey, have 5 invented a certain new and useful Improvement in Opera-Chairs; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

15 My present invention relates to seating appliances, and particularly to seating appliances comprising chairs interconnected in series, such as opera chairs.

In devising the improvements, herein set 20 forth, I have had in mind, in addition to providing a seating appliance which shall be durable in construction and afford a rigid and substantial support, so to construct the same that a series of the interconnected 25 chairs may be adapted to varying curves and floor inclines and adjustable to varying conditions in reference to space, whereby to secure a more perfect alinement of the chairs with reference to the aisles and economy in 30 seating space.

A further object is to construct the chairs so that they may be shipped to the floor in as compact form as possible and so far assembled that the work and skill required in 35 setting them up will be very materially reduced.

Referring to the accompanying drawings, in which my invention is fully illustrated, Figure 1 is a perspective view of the improved 40 seating appliance, showing three interconnected chairs; Fig. 2 is a view in side elevation of one of the chairs, its near side standard being shown in dot and dash outline; Fig. 3 is a vertical sectional view 45 through the structure comprising the seat and back; Fig. 4 is a full-size sectional view on the line $w-w$ of Fig. 2, Fig. 5 is a similar sectional view on the line $x-x$ of Fig. 2; Fig. 6 is a similar sectional view on the line $y-y$ of Fig. 3; Fig. 7 is a similar sectional view on the line $z-z$ in Fig. 3; and, Fig. 8 is a sectional view illustrating a 50 modification.

In said drawings a designates the side 55 standards each having an arm-rest b and a suitable base c of such character that each

side standard, when properly screwed to the floor, will be adapted to resist any forward and backward tilting action; in practice, where the chairs adjoin each other, as in a 60 row of chairs, it will be understood that each side standard serves for two chairs.

d designates the back and e the seat. According to the present construction, and by preference, the back and seat are pivotally connected together so as practically to constitute one structure, the side standards being separate, and suitable couplings are provided for connecting said structure with the side standards so that the side standards 70 may be first set up on the floor with reference to economizing the space available for a row of chairs between aisles and so that any desirable curvature in such row may be secured. To this end, the means whereby 75 the back and seat are pivotally connected together comprises the brackets f (Figs. 2 and 3). Each bracket is formed in two parts g and h suitably pivoted together at i . The part g is preferably a flat upright casting having on the inside the projections j to which the back may be secured, by rivets, screws or the like k , the lower projection being formed with a stop l against which the lower edge of the back may abut so that 80 in assembling the back with the brackets f the two brackets may be placed in true opposition to each other with a view principally to squarely aline the axes of the pivots i and thus prevent binding in said pivots 85 when the seat is raised or lowered. The part h may be of well known construction, comprising a flange m to which to secure the seat e ; to reinforce the seat, the parts h may be connected at the back by the bar n in a 90 well known manner. Each part g is formed with two elongated vertical slots o each opening, on the inside of said part, into an elongated socket p , the socket extending at both ends beyond the end of the slot; these 100 are placed the one preferably near the lower end of part g and the other preferably near the portion of part g which adjoins the arm-rest c when the chair is assembled, the lower one being thrust somewhat forwardly of 105 the other with a view to bring it as near to the center of gravity of the chair as practicable. Through the slots o are slipped the curved flat studs q having longitudinal slots r and each also formed at one end with the 110 pintle s , said pintle resting in and substantially fitting the socket p and thus acting

as a pivot for the stud and as a stop preventing the stud from being drawn clear through the slot. The upper studs are of course assembled with the brackets *g* before the back *d* is attached. The back, the seat and the means for pivotally connecting them being thus assembled and having the studs attached are now placed between the side standards, bolts *t* being passed through the side standards 10 and the slots of the studs to clamp the studs securely to the standards and thus support the back and seat; it will be understood, on reference to Fig. 1, that the same bolts may be used to clamp to the opposite sides of 15 an intermediate side standard the studs appropriated to the backs and seats of two adjoining chairs. In order to more substantially support the studs than would be afforded by the bolts alone the parts of the 20 side standards against which the studs bear may be recessed, as at *u*, Figs. 4 and 5, the studs substantially snugly fitting such recesses; as, in some instance, however, it might be desired that the back be capable of 25 adjustment to various inclines the recesses *u* may be omitted, (Fig. 8) thus allowing the couplings to assume such an angle as would be required for the incline desired.

My construction results in a compact, substantial and simple type of chair adapted for use as one unit of a row of chairs; each side standard being unitary, and the assembled hinged backs and seats being likewise so, these parts may be shipped to the floor 35 in only two lots, so that all that is then required is to bolt the studs to the side standards. The side standards are first set up, having properly spaced them with a view to economy of the available space and to secure 40 their proper alinement, both as to rows of chairs and with respect to the aisles, and then the backs and seats secured to them in the manner stated, the studs, by being pivoted and curved, readily adjusting themselves to varying conditions of space between said standards.

Having thus fully described my invention, what I claim as new and desire to secure by Letters Patent is:

1. The combination of the side standards, 50 the back, the seat, and means for supporting the back and seat on the side standards comprising hinged brackets, one part of each bracket carrying the seat and the other part carrying the back, and said means also comprising devices, pivotally attached to the upper and lower portions of said other parts of the brackets, for securing said brackets to the side standards, substantially as described. 55

2. The combination of side-standards, the back and seat members, and means for supporting one of said members on the side standards comprising an upper and a lower pair of studs curved laterally in a substantially horizontal plane, each stud connecting said member and a side standard and being pivoted in one and bearing in its curved portion against the other, substantially as described. 60

3. The combination of side-standards, the back and seat members, and means for supporting one of said members on the side standards comprising an upper and a lower pair of studs curved laterally in a substantially horizontal plane arranged the latter forward of the former, each stud connecting said member and a side standard and being pivoted in one and bearing in its curved portion against the other, substantially as described. 70

4. The combination of side standards, the back and seat members, and means for supporting one of said members on the side standards comprising curved studs, each stud 85 having a pintle at one end and said side standard and member having the one a slot receiving said stud and being shorter than the pintle thereof and the curved part of the stud being secured against the other of them, substantially as described.

In testimony, that I claim the foregoing, I have hereunto set my hand this 8th day of February, 1908.

ALBERT WANNER, JR.
